UNITED STATES PATENT OFFICE

2,490,689

PUNCHBOARD

John Edwin Kimsey, Spokane, Wash., assignor to
 L. W. Kimsey and R. L. Kimsey, both of Spokane, Wash.

Application February 28, 1946, Serial No. 650,891

8 Claims. (Cl. 273—139)

1

This invention relates to punch boards.

An object of the invention is the provision of a game having all the mechanism housed within a transparent casing, with a punch board having a face in close association with a flat inner face of the casing, said board being adapted to be revolved manually so that a transparent slide may be moved diametrically of the revolving board for placing a perforation in the slide in alignment with any of the pockets on the board, whereby a wad is located in the selected pocket, which wad will operate a lever for opening a switch for releasing a locking device that is forced into engagement with a gear connected with the operating mechanism for rotating the punch board, and a rack attached to the transparent slide, so that after a single punch has been made, the apparatus will be locked against further playing until the mechanism has been released by the insertion of a coin in a slot.

Another object of the invention is the provision of a game having a manually rotatable punch board in close association with a face of a transparent housing, so that the operator may view the entire face of the punch board, said punch board having a plurality of radially arranged pockets, with each pocket being filled with a wad of paper having certain indicia thereon, a horizontally disposed transparent slide being movable over the face of the punch board, so that a perforation in the board may be aligned with a selected pocket on the board, rotation of the punch board and the reciprocation of the slide cooperating to bring any of the pockets on the board in alignment with the perforation of the slide, so that the wad in the selected pocket may be punched therefrom, means in the casing and out of reach of the operator being employed for locking the rotatable board and the slide against unauthorized movement, until a coin has been inserted in a slot to cause release of the locking means, whereby the operator may rotate the punch board and reciprocate the slide to select a pre-determined pocket, means being employed in the casing and actuated by the punched wad for permitting the locking means to move into operative relation with the punch board and the slide, to prevent further movement of both the slide and the punch board.

A further object of the invention is the provision of a game in which a rotatable punch board is mounted within a transparent casing with the rotatable punch board cooperating with the transparent slide for selectively placing a pocket in the board in alignment with a perforation in

2

the slide, the usual wad which is punched from the pocket setting in motion instrumentalities which will lock the punch board and slide against movement, the instrumentalities being released by the insertion of a coin, the arrangement being such that only one punch may be made for each coin inserted.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

In the accompanying drawings the preferred form of the invention has been shown.

In said drawings:

20 Figure 1 is a longitudinal view in elevation of a punch board constructed in accordance with the principle of my invention.

Figure 2 is a longitudinal vertical section taken along the line 2—2 of Figure 5.

25 Figure 3 is a longitudinal vertical section taken along the line 3—3 of Figure 5.

Figure 4 is an enlarged transverse vertical section taken along the line 4—4 of Figure 1.

30 Figure 5 is a plan view of the punch board partly in section with the cover broken away.

Figure 6 shows more or less diagrammatically the electric circuits included in the machine.

Referring more particularly to the drawings, 10 designates the base member from which rise end walls 11 and 12 and side walls 13 and 14. As shown more particularly in Figures 1 to 3 inclusive, a dome-shaped portion 15 is located centrally of a housing, which is constituted by the various elements just described. The side walls 13 and 14 are extended upwardly and are connected to the dome-shaped portion 15. The face of the housing may be formed with transparent material so that the operator may view the entire mechanism within the housing.

45 A punch board generally designated by the numeral 20 is mounted rotatably at the center of the housing, with one face 22 of the board in close association with the inner face of the front wall 13 of the housing. The punch board 20 is in the form of a drum, having a plurality of radially arranged pockets 23 which extend entirely through the board, and each pocket is filled with a wad of paper containing certain indicia which will advise the operator when the 55 wad has been punched out of the pocket as to

what award he will receive. These wads are adapted to be dropped within a container 24 which is located directly below the punch board.

The punch board is supported by rollers 25 which have a groove through which a gear 26 moves. In other words, the grooved rollers straddle the gear 26. Each of the rollers is supported by a shaft 27.

A gear 28 is secured to a shaft 29, which extends through the front wall 13 of the housing and a manipulating knob 30, secured to the projecting end of the shaft, so that said shaft may be manually rotated for revolving the punch board 20, for a purpose which will be presently explained.

A gear 31 is also secured to the shaft 29 at the rear of the gear 28. A locking bar 32 (Figure 3) has a tooth 33 adapted to engage between a pair of teeth of a slidably mounted rack 34. This locking bar also has a tooth 35 adapted to engage between a pair of teeth of the gear 31. When the bar 32 is in this position, it would be impossible to reciprocate the rack 34 and rotate the shaft 29, therefore, it would be impossible to rotate the punch board 20.

An arm 40, secured to the locking bar 32, is operated by a solenoid 41 when the circuit to the solenoid is closed. In other words, when the solenoid is energized, the locking bar 32 will be withdrawn from the teeth of the gear 31 and the rack 34, to permit operation of the rack and likewise the punch board 20. On the other hand, when the solenoid 41 is de-energized, a spring 42 will force the locking bar 32 into operative engagement with the teeth of the rack and the teeth of the gear 31, in a manner which will be presently explained.

A transparent slide 45 covers a slot formed in the front face 13 of the housing, and is adapted to be reciprocated horizontally, so that a perforation 46 formed in the slide 45, may be moved over the pockets in the punch board 20. The slide 45 is at the exterior of the housing, so that it may be moved manually by the operator through the manipulation of the knobs 47. Pins 48 extend between the slide 45 and rack 34, so that they are connected for joint movement. Thus, the rack, when locked by bar 32, prevents movement by a player of the slide. Since the punch board may be manually rotated when the locking bar 32 has been released, the various radial lines of pockets may be placed in horizontal position and since the slide is adapted to be reciprocated in a horizontal plane, the perforation 46 may be placed over any of the pockets, through the combined operations of the rotatable punch board 20 and the slide 45.

A coin chute 50 has its upper end in communication with a coin slot 51 in a top 52 of the housing. The chute extends downwardly and terminates over a receptacle 52' to receive the coins inserted into the chute 50. Adjacent the lower end of the chute is a switch, containing the elements 53 and 54. When a coin is inserted in the slot 51, it will roll downwardly through the chute 50 and as it passes the switch, the elements 53 and 54 will be moved together to close an electric circuit which will be presently described.

The electric circuit which includes the switch elements 53 and 54 that are adapted to be closed by a coin, includes a grounded source of current 55, and a wire 56 which connects said source with a relay 57. The relay is grounded at 57 and

68 by means of the normally closed punch board contacts 65 and 66.

Switch element 54 is grounded while switch element 53 is electrically connected by a lead 62 to relay 57 and switch element 63 and by a lead 60 to solenoid 41. A lead 64 extends from solenoid 41 to current source 55.

Switch element 61 is carried by the armature of relay 57 and is connected electrically to the stationary element 65 of a switch.

The switch element 66 is connected to an arm 70 which is pivotally mounted at 71 within the housing. An arm or lever 72 extends from the arm 70 at the pivot point 71 and in a horizontal direction in line with the horizontal movement of the perforation 46 in the slide 45. This arm is in close association with the rear wall of the punch board 20, so that when a wad is forced out of a pocket in the punch board, it will press against the arm 72 and rock the same to move the switch element 66 out of engagement with the switch element 65, for breaking the circuit to the solenoid 41 to permit the spring 42 to force the locking bar 32 into operative engagement 20 with the gear 31 and the teeth of the rack 34 to prevent further rotation of the punch board 20 and reciprocation of the slide 45.

Referring more particularly to Figures 3 and 5, it will be seen that the rack 34 is supported in grooves of rollers 75, which are mounted for rotation on shafts 76, carried by the side walls of the housing.

An opening 78, formed in the front wall 13, is aligned with an opening in the container 24, so that when a wad is punched out of a pocket, it will drop into the container and fall through the opening 78, where it may be removed by the operator.

The shaft 29 (Figure 4) is supported by the front wall 13 and depending brackets 80. Sleeves 81, connected with the gear 31, and sleeves 82, connected with the gear 28, retain the gears 31 and 28 respectively, in alignment with the locking bar 32 and the gear 26 on the punch board 20.

The operation of my device is as follows:

When it is desired to operate the punch board, a coin of suitable denomination is inserted through the slot 51, so that it will roll downwardly in the chute 50 and close the switch elements 53 and 54, so that the circuit will be closed to the relay 57.

When coin chute contacts are closed by means of a coin they send the electric current to the coil 41 and also set the relay 57 which keeps the current flowing to the coil even after the coin chute switch elements 53 and 54 open up when the coin passes on through to the money box.

The coil 41 after the relay is set, will stay magnetized until the punch breaks the contact by passing through the board and opening the punch board contacts 65 and 66. This cuts the current and the relay switch opens to stop the flow of current to the coil 41.

The circuit is traced as follows. On the temporary closing of elements 53 and 54, current flows from source 55 through lead 64 to solenoid 41, thence through lead 60, through closed elements 53 and 54, and then returns through ground. At the same time, current flows from the source 55 through lead 56 to relay 57, energizing it and closing contacts 61 and 63. Current flows through these closed contacts through the already closed contacts 65 and 66, and returns through ground 60. When elements 53 and 54 open, the current will still flow from source 55

to solenoid 41, through leads 66 and 62 to the relay, and out of ground 68. The subsequent opening of contacts 65 and 66 as described above then opens the circuit.

The board cannot then be played until another coin starts the operation all over again.

The relay 57 is so timed that it will maintain the circuit to the solenoid 41 closed a sufficient length of time to permit the operator to not only rotate the punch board 20, but to reciprocate the slide 45 for positioning the perforation 46 in the slide directly over a selected pocket, at the front face of the board 20.

When the wad is punched from the pocket in the board 20, it will engage the lever 12 as before stated and rock the same, causing the switch element 66 to be moved away from the switch element 65, thereby breaking the circuit to the solenoid 41. As soon as this happens, the spring 42 will force the locking bar 32 into operative engagement with the teeth of the gear 31 and the teeth of the rack 34. Thus further operation of the punch board and the slide 45 will be impossible until the operator inserts another coin in the slot 51. In other words, the device is so constructed that the operator can only make a single punch for each coin inserted.

What is claimed is:

1. A game comprising a housing having a face part at least of which is transparent, said face being provided with an elongated slot, a transparent slide mounted in the slot for sliding movement longitudinally of the slot, said slide being provided with a perforation, a board rotatably mounted adjacent the face behind the slot, the slide being slidable in the slot for positioning of the slide in front of the board for placing the perforation selectively over a point on the board which may be punched by an instrument inserted through the perforation, and means causing the rotating board to be held against further rotation when the punch has been completed.

2. A game comprising a housing having a face provided with an elongated slot, a transparent slide mounted in the slot for sliding movement longitudinally of the slot, said slide having a perforation, a punch board rotatably mounted adjacent the face and provided with a plurality of pockets filled with wads, said slide being movable over the face for positioning the perforation over a selected pocket, so that a wad may be punched from said pocket, and means actuated by the wad when forced from the pocket for causing the slide and punch board to be held against movement.

3. A game comprising a housing having a face provided with an elongated slot, a transparent slide mounted in the slot for sliding movement longitudinally of the slot, said slide having a perforation, a punch board rotatably mounted adjacent the face and provided with a plurality of pockets filled with wads, said slide being movable over the face for positioning the perforation over a selected pocket, so that a wad may be punched from said pocket, means for locking normally the punch board and slide against movement, means causing release of the board and slide, and means actuated by the punched-out wad for causing the locking means to retain both board and slide against movement.

4. A game comprising a housing having a face part at least of which is transparent, said face being provided with an elongated slot, a slide mounted in the slot for sliding movement longitudinally of the slot, said slide having a perfora-

tion, a punch board rotatably mounted adjacent the transparent face and provided with a plurality of pockets filled with wads, said rotatable board cooperating with the movable slide for

5 selectively positioning the perforation over a pocket so that a wad may be punched from the pocket, a rack in the housing attached to the slide, a rotary means for operating the board, means normally engaging the rack and rotary 10 means for preventing actuation of the slide and board, means releasing temporarily the engaging means, and means actuated by the punched wad for returning the engaging means to normal position.

15 5. A game comprising a housing having a face part at least of which is transparent, said face being provided with an elongated slot, a slide mounted in the slot for sliding movement longitudinally of the slot, said slide having a perforation, a punch board rotatably mounted adjacent the transparent face and provided with a plurality of pockets filled with wads, said rotatable board cooperating with the movable slide for

20 selectively positioning the perforation over a pocket so that a wad may be punched from the pocket, a rack in the housing attached to the slide, means causing rotation of the board, a gear included in said means, a bar having teeth at its opposite ends normally in engagement with the

25 rack and gear for retaining the slide and board against movement, means causing temporary release of the bar from the rack and gear, and means actuated by the punched wad for returning the bar into engagement with the gear and rack.

35 6. A game comprising a housing having a face part at least of which is transparent, said face being provided with an elongated slot, a slide mounted in the slot for sliding movement longitudinally of the slot, said slide having a perforation, a punch board rotatably mounted adjacent the transparent face and provided with a plurality of pockets filled with wads, said rotatable board cooperating with the movable slide, for

40 selectively positioning the perforation over a pocket so that a wad may be punched from the pocket, a rack in the housing attached to the slide, means rotating the board and including a gear, a bar having teeth normally in engagement with the gear and rack for retaining the slide and board against operation, means including an electric circuit for causing release temporarily

45 of the bar from the rack and gear when the circuit is closed, a switch in the circuit, means operated by the punched wad for opening the switch, and means returning the bar into engagement with the gear and rack when the circuit is broken.

50 7. A game comprising a housing having a face part at least of which is transparent, said face being provided with an elongated slot, a slide mounted in the slot for sliding movement longitudinally of the slot, said slide having a perforation, a punch board rotatably mounted

55 adjacent the transparent face and provided with a plurality of pockets filled with wads, said rotatable board cooperating with the movable slide for selectively positioning the perforation over a pocket so that a wad may be punched from the pocket, a rack in the housing attached to the slide, means rotating the board and including a gear, a bar having teeth normally in engagement with the gear and rack for retaining the slide and board against operation, an electric circuit, a

60 70 magnetic means included in the circuit and when

energized, causing the bar to be withdrawn from the gear and rack for manual actuation of the board and slide, a switch in the circuit, means operated by the punched wad for opening the switch, and means forcing the bar into its normal reengagement with the rack and gear on opening of the circuit.

18. A game comprising a housing having a face part at least of which is transparent, said face being provided with an elongated slot, a slide mounted in the slot for sliding movement longitudinally of the slot, said slide having a perforation, a punch board rotatably mounted adjacent the transparent face and provided with a plurality of pockets filled with wads, said rotatable board cooperating with the movable slide for selectively positioning the perforation over a pocket so that a wad may be punched from the pocket, a rack attached to the slide, means rotat- 15 ing the board and including a gear, a bar having teeth normally engaging the track and gear to

retain the slide and board against movement, an electric circuit, a magnetic means included in the circuit and when energized, causing the bar to be withdrawn from the gear and rack for manual operation of the board and slide, a switch in the circuit, a lever having an arm extending along the path of the perforation in the slide and adapted to be rocked by a punched wad, said lever being connected to the switch for opening the same, and a spring for returning the bar into its normal engagement with the gear and rack when the circuit is broken.
